UNITED STATES PATENT OFFICE.

ENOS L. WALKER, OF ST. LOUIS, MISSOURI.

BERRY-BOX CRATE.

SPECIFICATION forming part of Letters Patent No. 625,525, dated May 23, 1899.

Application filed May 31, 1898. Serial No. 682,153. (No model.)

To all whom it may concern:

Be it known that I, ENOS L. WALKER, of the city of St. Louis, State of Missouri, have invented certain new and useful Improvements in Berry-Box Crates, of which the following is a full, clear, and exact description, reference being had to the accompanying drawings, forming a part thereof.

My invention relates to berry-box crates; and it consists of the novel construction, combination, and arrangement of parts herein-after described and claimed.

Figure 1 is a plan view of a berry-box crate of my improved construction, parts thereof being broken away to more clearly illustrate the same and showing the berry-boxes removed from one portion of said crate. Fig. 2 is an enlarged longitudinal sectional view taken approximately on the line 22 of Fig. 1.

Referring by numerals to the accompanying drawings, 1 1 indicate the end pieces of my improved crate, and 2 the transversely-arranged partition which is constructed of material somewhat thicker than the end pieces 1, and to the ends of said end pieces 1 and said partition are secured by nails or in any suitable manner the usual side pieces 3, and a suitable bottom 4 is secured to the lower edges of said end pieces and partition.

Formed oppositely on the inner faces of the end pieces 1 and on the side faces of the central partition 2 at points half-way between the top and bottom edges of said end pieces and partition are ledges 5, the same extending approximately half-way through the thickness of the end pieces 1 and a quarter of the way through the partition 2, and the material in the faces of the end pieces and partition immediately above said ledges is cut away on a gradual curve, thereby producing opposite recesses, which are tapered from the said ledges upward, as indicated by 6, until the original face or surface of the end pieces and partition 2 is reached, this point being approximately half-way between the ledges 5 and the tops of the end pieces and partition.

By so forming these ledges 5 a substantial resting-place is formed for the ends of the removable horizontally-arranged partitions 7, which when properly located form a top for the box in the lower part of the crate and a base upon which are located the boxes in the

top half of the crate. These removable partitions can only be removed by lifting one end at first, as indicated by dotted lines in Fig. 2, and when placed in position one end is first placed upon one of the ledges and the opposite end travels downwardly through the recess or cut-away portion 6 until said last-mentioned end rests upon this ledge.

By reason of the construction of ledges 5 and oppositely-tapered recesses 6 the partitions will be held in position against accidental displacement by gravity when the crate is overturned. This result will be occasioned by the fact that the walls of said recesses converge upwardly, and the ends of the said partitions will be caught and intercepted and held in position thereby during the act of falling. In falling both ends of the partitions being substantially of the same weight will of course gravitate downwardly with approximately the same velocity, and the result just mentioned will thereby be produced.

In packing a berry-box crate of my improved construction the bottom of the crate is first filled with the boxes, after which a removable partition 7 is located over each row of the boxes, said partitions being properly manipulated until their ends rest upon the ledges, as hereinbefore described, after which the second tier or layer of boxes is located upon said partitions, thus filling the box, after which the crate-cover is nailed or secured in position.

By my improved construction much space is economized in a berry-box crate, the removable horizontal partitions are prevented from coming in contact with the tier or layer of boxes which they cover, and no auxiliary ledges or supports that extend outwardly from the end pieces and partition are made use of, which construction would result in a loss of space in the crate, and said crates can be very cheaply manufactured and are very efficient in use.

It is obvious that my improved construction can be applied to egg-crates and all boxes or crates where removable horizontal partitions are used.

I claim—

1. The improved berry-box crate, having end pieces in which are formed opposite re-

cesses, the walls of which converge toward each other, in combination with removable partitions located in said recesses and arranged to be caught and supported upon the converging walls of said recesses when the crate is inverted, substantially as specified.

2. The improved berry-box crate, having the end pieces 1, the partition 2, the opposite faces of said end pieces and said partition 10 having opposite converging recesses 6 which terminate in ledges at their lower ends, and

the removable horizontal partitions located in said recesses and normally retained therein by the converging walls of said recesses, substantially as specified.

In testimony whereof I affix my signature in presence of two witnesses.

ENOS L. WALKER.

Witnesses:

M. P. SMITH,
A. W. TYLER.
